UNITED STATES PATENT OFFICE.

WILLIAM LEE CHURCH, OF NEWTON CENTER, MASSACHUSETTS, ASSIGNOR TO UNIFORM COMPANY, A CORPORATION OF MASSACHUSETTS.

ADJUSTABLE SHORE.

1,426,359.

Specification of Letters Patent. Patented Aug. 22, 1922.

Application filed August 5, 1919. Serial No. 315,446.

To all whom it may concern:

Be it known that I, WILLIAM LEE CHURCH, a citizen of the United States, residing at Newton Center, in the county of Suffolk and State of Massachusetts, have invented certain new and useful Improvements in Adjustable Shores, of which the following is a specification.

This invention relates to shores or struts 10 for supporting forms for concrete work and the like, and it has for one of its primary objects the provision of an improved shore which will form permanent equipment, capable of repeated use and ready shipment, 15 in contradistinction to the temporary shoring which is ordinarily constructed on the ground and discarded upon the completion of the operation.

Another object of the invention resides in 20 the provision of an improved collapsible head for shores.

My invention also contemplates the provision of improved means for rendering the shore adjustable, the arrangement being 25 such, however, that the parts of the shore are positively held in positions of adjustment and settling of the shore is prevented.

Still another object of my invention resides in the provision of an adjustable shore 30 in which very close adjustment is obtained, and in which, in addition, wear on the parts is reduced to a negligible factor.

I accomplish the foregoing together with such other objects as may hereinafter appear, by means of a construction, the preferred embodiment of which I have illustrated in the accompanying drawings wherein—

Figure 1 is a fragmentary side elevation 40 of a shore embodying my improved collapsible head; Figure 2 is a side elevation of the head in position of collapse; Figure 3 is a side elevation of the upper portion of the center support of the shores; Figures 4 and 5 are side elevations of a modified form of 45 head cross piece; Figures 6, 7 and 8 are side elevations of the shore showing the means whereby the same may be adjusted in height and illustrating the manner in which adjustment is effected; Figure 9 is a perspective of a detail of my invention whereby it is possible to obtain very close adjustment of the shore to the work; and Figure 10 is a perspective of a modification of the device 50 shown in Figure 9.

Referring now to Figures 1 and 6, it will be seen that the shore comprises the center support 7; the side members or pieces 8; and the collapsible head, indicated as a whole by reference letter A.

The head comprises the cross piece 9 and the braces 10. The head is detachably supported on the strut as follows:

On each of two opposite sides the center support 7 is provided with a cheek 11, preferably in the form of a metal plate secured to the top of the center support by any preferred means, such for example as the screws 12, the upper edges of the cheeks projecting slightly above the top of the support. The cross piece 9 is provided with a pair of oppositely disposed downwardly projecting members such, for example, as the angle irons 13, secured to the lower face of the cross piece and spaced apart so as to fit the end of the center support. The cross piece is of such width as to fit neatly between the cheeks 11. It will be seen that by this arrangement the cross piece, when set down on the end of the center support, will be automatically centered thereon and held as against rotation, as well as movement relative to the center post or support in any lateral direction. The braces 10 secure the cross piece to the center support and also 85 brace the cross piece. Each brace is bolted to the cross piece by means of a bolt 14 for swinging movement relative thereto. The braces are secured to opposite faces of the cross piece and at the lower ends they are apertured to receive the bolt 17, which is adapted to be also passed through the bolt hole 18 of the center support. It will be seen that by this arrangement the head is 90 securely but detachably fastened to and supported from the center support.

In order that the head may be collapsed into compact form, suitable for shipment, I provide a hole 19 in the cross piece 9 midway between the holes for the bolts 14; 100 and in each brace 10, I drill a hole 20 at such a point that when the braces are swung to the position shown in Figure 2, the bolt holes 19 and 20 will coincide so that the bolt 17, previously withdrawn in order to 105 permit the removal of the head from the center support, may be utilized to secure the parts in the position shown in said figure. No extra parts are thus required.

In Figures 4 and 5, I have shown modi- 110

fications of the means for centering the cross head on the center support. In the construction of Figure 4, I provide a pin 21 adapted to fit into a hole drilled in the 5 top of the center support; and in Figure 5, I cut a shallow groove or recess 22 in the lower face of the cross piece of a width sufficient to fit the center support.

Referring now to the means for adjusting the shore as to length to suit the particular work in hand, I provide the side pieces 8 with a plurality of holes *a*, *b*, *c*, etc., preferably spaced equidistantly, and I provide the center support with a plurality of holes 15 *a'*, *b'*, *c'*, etc., also preferably spaced equidistantly, the distances between the holes *a*, *b*, *c*, etc. being slightly greater than the distances between the holes *a'*, *b'*, *c'*, etc. For purposes of illustration this difference 20 between such distances may be taken as one inch, the distance *a*—*b* being 6" and *a'*—*b'* 5".

Referring now to Figure 6, when the center support 7 is in lowermost position, the 25 holes *a* and *a'* will be in alinement, which will bring the holes *f* and *f'* and the holes *k* and *m'* into register. Bolts 23 may be passed through any desired number of the alined or registering openings. With the 30 parts in the position shown in Figure 6 there will be no extension of the shore and assuming that an extension of one inch is desired, the center support is raised one inch which will bring holes *b* and *b'*, *g* and 35 *h'* and *l* and *n'* into alinement for the reception of bolts 23. For every additional inch in length desired, the center post is raised, bringing into registry other sets of bolt 40 openings.

In Figure 8 I have illustrated a 23 inch extension which brings the openings *i* and *i'* into registry for the reception of a bolt. It will be noted that as the shore is extended the position of the bolts rises until 45 with a 23 inch extension, as shown in Figure 8, the upper bolt is in the top holes in the side pieces and the lower bolt comes above the center of the side pieces. If now an additional extension of one inch be made 50 the openings *e* and *e'* will coincide thus bringing the bolts into lowermost position, i. e. with reference to the center support, and permitting of a still greater extension of the strut. For all practical purposes an 55 extension of 29 inches will suffice and for this extension 7 ft. side pieces will be required.

It will be seen that the adjustment depends upon the differential relation of the 60 bolt openings, which may be said to be graduated as to spacing somewhat in the nature of a vernier scale.

It will be noted from the foregoing that a wide range of adjustment is made possible 65 by this arrangement and it is further to be

noted that the shore is positively held in positions of adjustment so that settling cannot take place and there is little or no wear on the parts. It will of course be understood that my invention is not limited to 70 the precise graduation specified, but I have found this to be the most satisfactory under practical service conditions.

If closer adjustment is required, particularly where it is desired to avoid the use 75 of wedges, I provide the supplemental devices shown in Figures 9 and 10. In adapting the shore for the application of such a device as is shown in Figure 9, I cut off a piece about 6 inches in length from the 80 lower end of the center support 7 and drill holes in the side pieces for the reception of a bolt 24 on which the substantially square block 25 may be revolvably supported between the side pieces. The bolt receiving 85 hole in the block is located to one side of the true center thereof, as for example two inches from the bottom face AB of the block, two and one quarter inches from the face CB, two and one half inches from the face CD, and two and three quarter inches from the face DA. The width of the block is such that the block fits neatly between the side pieces so that it may be rotated when the bolt is eased off and tightly clamped 90 between the side pieces when the bolt is tightened.

When the face AB is down, it will be flush with the ends of the side pieces, and there will be no extension of the shore. If 100 the block be now turned to the right one quarter, so that the face BC is at the bottom, there will be an extension of the shore one quarter inch, for the reason that the face BC will project one quarter inch beyond the 105 ends of side pieces. If the block be turned one half, the face CD will be at the bottom and the extension of the shore will be one half inch, and if the face DA is at the bottom, the extension will be three quarters of 110 an inch. Thus, for example, after the main adjustment has been effected as hereinbefore pointed out, a finer adjustment in quarter inches may be had.

If a still closer adjustment is required 115 this can be accomplished by means of the modification of Figure 10, in which, instead of providing a substantially square block as shown in Figure 9, I provide an irregular or distorted octagonal block with the radii 120 to the different faces varying by increments one one-eighth of an inch, say for example from two inches to two and seven-eighths inches. Such a block becomes in effect a virtual cam.

I claim:

1. A shore comprising in combination a supporting member and a collapsible head therefor, comprising a cross piece and a pair of braces pivoted to the cross piece for 130

swinging movement with reference thereto, means for detachably securing the braces to the supporting member, and means for holding the braces in position of collapse on the 5 cross piece.

2. A shore comprising in combination a supporting member and a collapsible head, said head comprising a cross piece and brace members pivotally secured at one end to said 10 cross piece, means for detachably securing the other ends of the braces to the supporting member, and means whereby said last mentioned means may be utilized in holding the braces in collapse position relative to the cross piece.

3. A shore comprising in combination a supporting member and a collapsible head, said head comprising a cross piece and braces pivotled at one end to said cross piece, 20 a bolt adapted to detachably secure the opposite ends of the braces to the supporting member, and bolt openings in the braces and cross piece adapted to register when the braces are collapsed whereby said bolts may 25 be utilized in holding the members comprising the head in position of collapse.

4. A shore of the character described comprising in combination a supporting member, a detachable head, inter-engaging means on said support and head for relatively positioning said members, said means comprising a pair of spaced angles secured to the lower face of the head and a pair of plates secured to opposite faces of the supporting member and projecting thereabove, and means detachably securing the head to the support.

5. A shore of the character described comprising in combination a supporting member, a collapsible head, inter-engaging means on said support and head for relatively positioning said members, and comprising a pair of spaced angles secured to the lower face of head and a pair of plates secured to opposite faces of the supporting member and projecting thereabove, said collapsible head including a pair of braces

pivoted thereto, and means for detachably securing the braces to the supporting member.

6. An adjustable shore of the character described comprising in combination one member provided with a plurality of holes equally spaced and a second member also provided with a plurality of holes equally spaced but the distance between holes being of a different dimension than on the first member, said members being relatively movable and the relation between the two sets of holes being in effect that of the markings 55 on a vernier scale, and said members being of sufficient length to bring at least two pairs of holes in alignment in all positions of normal working adjustment between the members, and a supporting member adapted 60 to be passed through the aligned holes.

7. An adjustable shore of the character described comprising in combination a pair of cooperating relatively movable members each of which is provided with a set of 70 means for support, the relation between which sets is that of the markings on a vernier scale, said members being of sufficient length to bring at least two pairs of the means for support in alignment in all 75 positions of normal working adjustment between the members, and supporting members adapted to be applied to the pairs of aligned means for support.

8. The combination with a shore comprising 80 members expansible in given increments after the manner of a vernier scale as described, of an expansible element cooperating therewith consisting of a turnable prismatic member, the supporting faces of 85 which are differently spaced, and the spacing increments of which are smaller than said first mentioned increments whereby more close adjustment of the shore can be obtained.

In testimony whereof I have hereunto signed my name.

WILLIAM LEE CHURCH.
